The H. Campfield
ATTORNEY.

UNITED STATES PATENT OFFICE.

THEODOR DUBYK, OF PASSAIC, NEW JERSEY.

RACK.

Application filed March 15, 1922. Serial No. 543,888.

To all whom it may concern:

Be it known that I, THEODOR DUBYK, a citizen of Poland, and a resident of Passaic, county of Passaic, and State of New Jersey, 60
have invented certain new and useful Improvements in Racks, of which the following is a specification.

This invention relates to an improved rack that is of the type that is adapted to 65
10 be secured preferably in a window casing and can be extended to support the line, on which the clothes are pinned, substantially straight, or it can be folded so as to not materially project from the 15 house.

The invention is designed to provide a rack which, in its folded position, can be swung, in case it is mounted in a window casing, so that it can be extended inside of 20
20 the house and clothes can be put on the rack or taken from it without the necessity of the person doing it leaning from the window.

The invention also consists in certain details of construction to be hereinafter more fully described and finally embodied in the 25 claims.

The invention is illustrated in the accompanying drawings, in which Figure 1 is 30
30 a side view of a rack made according to my invention, the view showing a small size rack mounted in a window casing, the window casing being shown in section. Figure 2 is a detail section on line 2—2 in Figure 35
35 1. Figure 3 is a top view of the rack shown in Figure 1, with the top bar or plate removed. Figure 4 is a perspective view showing the arms of the rack where they are jointed together; parts of the joint 40
40 being shown separated. Figure 5 is a view of a plate adapted for securing the top part of the rack to a window casing, and Figure 6 is a perspective view of a bar which forms part of the support.

The bracket on which the clothes line is supported is extensible and contractible, and in the form shown consists of toggles made in three sets, the levers 10 of the top set being substantially horizontal, the toggles 45
50 50 11 being secured to one end of the upper set and extending down on one side, and the toggles 12 being secured to the other end of the horizontal set and extending downward, being joined at their lower ends by pivotal connections. It will thus

be seen that since the toggles 11 and 12 are pivotally connected at their centers, as at 55
13, and the toggles 10 of the upper set are pivotally connected intermediate of their ends, as at 14, the whole device can be simultaneously moved, when the device is extended the clothes lines 15 and 16 being extended and being held substantially straight, and when the device is contracted or folded in the clothes lines will, of course, become looped and be suspended from their connections.

One form of lower pivotal connection is illustrated in Figure 2, the toggle levers 11 and 12 being connected pivotally to the bolt 60
17, and to reduce wear and friction on the levers I usually place a washer 18 between the ends of the toggles, and a ring 19 with an eye 20 thereon is secured on the bolt 17 by the nut 21, this connection being made at each successive joint, and the line 16 is therefore held in position, the ends, of course, being secured by knotting or other suitable means.

The upper pivotal connection of the sets of 65
70 toggle levers is shown in detail in Figure 4, the levers 10 being pivoted on the bolt 22, this bolt being a right-angle bolt, the ends 23 of it receiving the toggle levers 11 on one side and the toggle levers 12 on the other, these being secured in position first and then the ring 24 to which the line 15 is secured is placed on the bolt, and then the nut 25, when screwed on the end 23, holds the parts in pivotal relation.

At one end of the bracket the top joints are secured to yokes 26, these, of course, being arranged so that they can extend or move from each other in a lateral direction when the bracket is contracted, and move toward each other when it is extended, and to make this movement easy I prefer to provide the yokes 26 with rollers 27 rotatably mounted on the bottom bar of each yoke which rollers bear against the flange 75
80 85 90 95 100 of the bar 29.

When it is desired to make the rack so that it can be swung horizontally, or, if necessary, entirely reversed and swung within the house, the bar is mounted on a rod, which rod also supports the lower toggle joint by means of the collar 30 slidably arranged on the rod 36, the rod 36 being secured in a suitable foot 31 at the bottom and a plate 32 at the top. The 105
110

plate 32 is adapted to be fastened to the outer sides of the window casing, and in the form shown the extensions 33 are fitted against the outside of the window casing 5 34, and this plate is shown more clearly in Figure 5, but the illustration shows it upside down so as to clearly indicate the cutting away of the flange 35 at its ends, usually to a length to fit just within the 10 window casing.

The rod 36, the collar 30, the yokes 26 and the bar 29 form a support for the bracket at one end, and are preferably made rotatable, the bar 29 having an opening 37 in its 15 center, through which the rod 36 passes, and the ends 38 are provided with openings 39 which are adapted to be placed in register with the openings 40 in the flange of the plate 32, being secured by suitable bolts 41 20 and the wing nuts 42.

The device is usually arranged as shown in Figure 1, so that it is placed entirely outside the window sashes, and the window can be shut, and when it is to be used the 25 bar 29 is released by loosening the fastening means that hold the bar 29 in position, either the bolts 41 or any equivalent means, and when the rack is contracted the bar can be swung around, which carries with it 30 the yokes 26 and the bracket, and then the device can be extended, it being shown partly extended in dotted outline in Figure 1. The clothes can be fastened to the lines 16 and 17, and it will be noted in this connection that the triangular bracket supports these lines in different vertical planes and the clothes on one will not interfere 35 with the clothes on the other. After the bracket has received articles on the lines 40 it is folded, and the clothes, of course, fold with it, and it can then be swung around to the outside and then extended so as to

pull the lines until they are substantially straight, and the clothes are suspended on such straightened or stretched lines. This 45 operation, of course, is reversed when the clothes are to be taken in.

The triangular bracket makes a substantially stiff structure that does not sag appreciably even when filled with wet clothes, 50 and its operation is easy because the collar 30 slides easily on the rod 36, and the rollers 27 permit easy side motion of the top joint at the end of the bracket.

I claim:

1. A rack comprising an extensible bracket having means thereon at separated points for suspending a clothes line, a clothes line of a length to be substantially straight when the bracket is extended, a 60 rotatable support for holding the bracket, and means for locking the support in different rotative positions.

2. A rack comprising an extensible bracket having means thereon at separated points for suspending a clothes line, a clothes line of a length to be substantially straight when the bracket is extended, a support for holding the bracket, a post on 65 on which the support is rotatably mounted, 70 a bar in which the post is secured, and means for locking the support to the bar in reversed positions.

3. In a rack, a bracket formed of three sets of toggles connected together to form 75 a triangular bracket in cross-section, a line attached to the bracket at separated points so as to be extended with it, and means at one end for supporting the bracket.

In testimony that I claim the foregoing, 80 I have hereto set my hand, this 14th day of March, 1922.

THEODOR DUBYK.
